HENRI SCHNEIDER, OF LE CREUSOT, SAÔNE-ET-LOIRE, FRANCE.

HYDRAULIC BRAKE FOR CHECKING AND CONTROLLING THE RECOIL OF ORDNANCE.

SPECIFICATION forming part of Letters Patent No. 415,569, dated November 19, 1889.

Application filed February 20, 1889. Serial No. 300,618. (No model.)

To all whom it may concern:

Be it known that I, HENRI SCHNEIDER, manager of the firm Schneider & Cie., of Le Creusot, (Saône-et-Loire,) in the Republic 5 of France, have invented Improvements in Hydraulic Brakes for Checking or Controlling the Recoil of Ordnance, of which the following is a specification.

This invention relates to a hydraulic brake 10 enabling the rate of recoil of ordnance to be checked or controlled in accordance with clearly-defined laws, whereby the strain upon the mounting is reduced to a minimum. The principle upon which the construction of this 15 brake is based is as follows: A given quantity of liquid contained in a chamber is compressed by the recoil resulting from the discharge of the gun and escapes through a number of orifices, which are closed one after the other by 20 the movement of the recoil. The forced escape of liquid through these orifices, which gradually diminish in number, opposes to the movement of the gun a resistance proportionate to the speed of recoil, the said resistance 25 being dependent on the number and area of the orifices.

Figure 1 is a sectional view of one form of my improved hydraulic brake for checking the recoil of ordnance. Fig. 2 is a similar 30 view of another form; and Figs. 3 to 7, inclusive, are corresponding views of various other modified forms of my invention.

According to the arrangement illustrated in Fig. 1, a liquid contained in a chamber or cavity connected to the carriage fills a tube B, in which works a piston A, rigidly connected to the stationary frame or platform by its rod. The tube B is perforated at intervals along a helical line, for example, with 35 a certain number of orifices o, the number and sectional area of the said orifices being determined by suitable calculations. At the moment when the recoil commences all the orifices are in front of the piston A, and the compressed liquid in the tube can escape through all the orifices; but in proportion as the cylinder moves backward the number of orifices open to the liquid diminishes in front of the piston, owing to the action of the recoil 45 50 the total area of the outlet thus growing less and less. It thus becomes possible by regu-

lating the dimensions, number, and position of the orifices o to modify or control the rate or speed of recoil to any desired degree.

When the gun is run out in battery, the 55 brake operates in the same way—that is to say, the total section of the outlet, being considerable at the commencement, gradually diminishes to zero, if necessary, to deaden the shock of the carriage on the frame or platform. The piston A and tube B thus constitute a very simple brake, opposing to the movement of the gun a resistance proportionate to the effect of the discharge. The amplitude of the recoil consequently remains the 60 same for all angles of laying, the said amplitude being dependent solely on the area, number, and position of the orifices o. This brake in no way interferes with the handling of the gun in the operations of running in or 65 out, and it effectually prevents any sudden running in of the carriage.

In the foregoing example the tube is moved by the recoil and the piston is fixed; but this arrangement may be reversed in certain cases, 70 the piston being movable and the tube stationary, the result being evidently the same in either arrangement.

It is not necessary for the tube B to be cylindrical. It may be of polygonal, elliptic, 75 or other suitable form in transverse section, the piston being of course shaped to fit the interior of the tube.

Several similar brakes may be employed on the same mounting, being regularly arranged 80 in horizontal, inclined, or even vertical positions. In the latter case they serve to diminish the effect of concussions.

Fig. 2 represents a brake of the same kind in which the piston-rod acts by compression 85 or with a thrusting action. In Fig. 3 the piston-rod acts with a pulling action. In these two examples the piston is provided with a rod on one side only, and the apparatus consequently takes up less room. As before, 90 these pistons may be stationary and the cylinders or tubes movable.

Figs. 4, 5, 6, and 7 illustrate modifications in the construction of the brake; but the principle is the same.

In the arrangement illustrated in Fig. 4 the tube B is dispensed with, the piston be-

ing made longer and forming a hollow plunger sliding in a correspondingly-formed orifice in a partition C. This hollow plunger is provided on its circumference with orifices o, 5 which during the recoil pass successively from one side of the partition to the other, thus diminishing the area of the outlet for the liquid in proportion to the speed of the recoil.

10 In the arrangement illustrated in Fig. 5 the liquid contained in cavities or chambers D is forced out by solid plungers E E, and drives out a compensating plunger F after passing through orifices o, formed in a hollow 15 rod or plunger attached to the compensating plunger. The number of orifices open to the flow of liquid decreases from the commencement of the movement as they pass to the other side of a partition h, and the area of 20 the passage for the escape of liquid is consequently contracted in the required proportion. The chambers or cavities D, which may be of any suitable shape, simply require to be provided with tight-fitting guides or stuffing- 25 boxes for the passage of the plungers, and consequently require very little fitting. Any desired number of compressors may be employed, being arranged in the most convenient position, and they may be fixed or movable, the chambers being movable or fixed accordingly.

Any suitable relation or proportion may exist between the compressor and the compensating plunger. The compensator may be of 35 annular form, as indicated in Fig. 6, or may partly inclose or surround the compressing-plunger. In this case the area of the compensator-tube B in transverse section is a multiple of the area of the plunger. Its stroke 40 is consequently shorter, and it is guided on one hand by a stuffing-box L and on the other hand on a stationary rod J. The liquid in the space between the rod J and the compressor A is compressed by the recoil, and escapes through the orifices o, which are gradually closed one after the other as the compressor enters the compensator. The area of 45 the passage for the flow of liquid also decreases according to the number, size, and 50 position of the orifices and in proportion to the speed of the recoil.

Fig. 7 is a modification of the arrange-

ment illustrated in Fig. 4. A hollow plunger M, perforated with orifices o on its circumference, slides through a partition C, separating 55 a chamber N from a chamber P, being attached to a rod a, for example. The liquid expelled from the chamber P flows through the orifices o, which pass in succession from one side of the partition C to the other. The 60 area of the passage for the escape of the liquid is also diminished progressively and in accordance with the number, size, and position of the orifices o.

I may apply my invention to field, siege, 65 port, battery, naval, turret, and other mounting for ordnance.

I may employ, according to circumstances, the arrangements illustrated in the annexed drawings, or such others as study and experience may suggest in accordance with the principle hereinbefore specified. I may also employ any suitable metals in the construction of the improved brakes, and may vary the forms and dimensions of the accessory 70 parts according to the effect to be produced. Any suitable liquid may be employed, but preferably a liquid or mixture not liable to congeal.

I claim as my invention—

1. The combination of a piston of a hydraulic brake for controlling the recoil of ordnance with a chamber containing liquid to be compressed by the recoil of the gun, and a series of orifices for the escape of the liquid 85 from such chamber, and means for closing the orifices one after the other by the movement of the recoil, substantially as described.

2. The combination of a piston with a chamber, one for connection to a gun and the other to a fixed point, and a chamber containing liquid and the piston and having a series of discharge-orifices adapted to be closed one after the other by the movement of the piston within the chamber, as and for the purpose set forth.

In testimony whereof I have signed my name to this specification in the presence of two subscribing witnesses.

HENRI SCHNEIDER.
